PORTABLE CARTRIDGE TAPE PLAYER

Takeshi Sasaki, Tokyo, Japan, assignor to Motorola,
Inc., Franklin Park, Ill.

Filed Jan. 7, 1970, Ser. No. 20,801

Term of patent 14 years

Int. Cl. D14—01

U.S. Cl. D26—14

FIG.2

FIG.3

FIG.1

FIG.5

FIG.4

FIG.6

FIG. 1 is a front elevation view of a portable cartridge tape player showing my new design;

FIG. 2 is a top plan view;

FIG. 3 is a left side elevation view with respect to FIG. 1;

FIG. 4 is a rear elevation view;

FIG. 5 is a right side elevation view with respect to FIG. 1; and

FIG. 6 is a bottom plan view.

The apertured pattern is understood to continue uniformly throughout the rectilinear areas disclosed in FIGS. 1 and 4 on the drawing.

I claim:

The ornamental design for a portable cartridge tape player, as shown and described.
